HEADER FOR A BODY-FLUID DRAINAGE BAG

Edgwin R. Polk, Fords, N.J., Sidney Polansky, Great Neck, N.Y., and Louis Mirando, Upper Saddle River, N.J., assignors to Packaging Associates, Inc.

Filed Jan. 13, 1970, Ser. No. 21,173

Term of patent 14 years

Int. Cl. D24—99

U.S. Cl. D83—1

FIG. 1

FIG. 2

FIG. 3

FIG. 4

FIG. 1 is an elevational view of a header for a body-fluid drainage bag showing our new design;

FIG. 2 is a top plan view;

FIG. 3 is a bottom plan view; and

FIG. 4 is an end view.

We claim:

The ornamental design for a header for a body-fluid drainage bag, substantially as shown.
